UNITED STATES PATENT OFFICE.

ADAM A. SERVA, OF CANTON, OHIO, ASSIGNOR TO THE UNITED ELECTRIC COMPANY, OF CANTON, OHIO, A CORPORATION OF OHIO.

BRUSH ATTACHMENT FOR FLOOR POLISHERS.

Application filed November 6, 1924. Serial No. 748,065.

This invention relates to brushes for cleaning and waxing hardwood floors and similar polished surfaces, and is more particularly a brush attachment arranged to be detachably connected upon a floor polisher of the type illustrated and described in United States Letters Patent No. 1,346,918, to Eugene L. Snyder, dated July 20, 1920, and an improvement thereof disclosed in my Patent No. 1,585,269, dated May 18, 1926.

Floor polishers of this character comprise a V-shaped head provided with two polishing surfaces, and the objects of the present improvement are to provide a brush arranged to be easily and readily attached to or detached from the polishing head to apply the wax or cleaning agent, after which the brush is detached and the floor or other surface is polished with the floor polisher in the usual manner.

The above and other objects may be attained by providing a rearwardly and downwardly inclined plate upon the upper surface of the brush for the purpose of maintaining stability and preventing tilting of the brush, as well as to equalize the pressure over the entire brush surface.

This plate has a curved rib at its rear edge to engage the rear edge of one side member of the polishing head, a pair of spring arms being provided upon the sides of the brush and having apertures for engagement with transversely disposed bosses upon the polishing head.

The improved brush attachment is illustrated in the accompanying drawing, in which—

Figure 1 is a side elevation of the floor polisher, showing the improved brush attachment connected thereto;

Fig. 2, a transverse section upon the line 2—2, Fig. 1; and

Fig. 3, a detached perspective view of the brush attachment.

Similar numerals refer to similar parts throughout the drawing.

The floor polisher for which the present brush attachment is intended, comprises a V-shaped polishing head having the two converging side members 1, a vertical longitudinal rib 2, to which the operating handle 3 is connected, and a transverse wall 4

having a boss 5 upon each end for the attachment of the spring 6, which retains the polishing cloth 7 upon the head.

The back 8 of the brush is of a width slightly greater than the width of the polishing head, and is considerably longer than the head.

A metal plate 9 of substantially the same length as one face of the polishing head, is mounted upon the back in a rearwardly inclined position, the rear portion of the plate being attached to the back of the brush as by tacks 11 or the like, the rear free end of the plate being curved upward and forward, as shown at 12, to engage the rear curved edge of one side member of the polishing head. A downwardly inclined flange 13 is provided at the forward end of the plate 9 and connected to the forward end of the back of the brush, as by tacks 14 or the like.

A spring arm 15 is rigidly attached to each side edge of the brush back at a point substantially midway between the ends of the plate 9, and is provided with the inwardly disposed portion 16, terminating in the off-set end 17, provided with an opening 18 arranged to receive the adjacent boss 5, as shown in Figs. 1 and 2. For the purpose of permitting the spring arms to be quickly centered upon the bosses, an outwardly curved spring finger 19 may be formed at each side of the aperture 18.

From the above, it will be obvious that when it is desired to apply the wax or cleaning agent to the floor, it is only necessary to engage the rear end of one of the side members of the polishing head against the curved rear end 12 of the plate 9, and to snap the spring arms 15 into position over the ends of the bosses 5, thus retaining the brush upon the polishing head.

By inclining the plate 9, the weight of the polishing head is thrown further toward the rear end of the brush, distributing the weight more evenly than if the head were located in the normal position, thus maintaining the brush in its normal position and preventing tilting of the same.

The brush attachment is thus applicable to the form of floor polisher which is illustrated and described in my co-pending application executed of even date with the

present application, and no change in said floor polisher is required in order to accommodate the brush.

I claim:—

5 An attachment for a V-shaped polisher head formed of a pair of converging side members having lateral bosses between said side members, said attachment comprising a brush having a rearwardly inclined upper

surface for contact with either of said side 10 members of the head, spring arms upon the brush for engagement with said bosses and an upturned flange upon the brush for contact with the rear end of the head.

In testimony that I claim the above, I 15 have hereunto subscribed my name.

ADAM A. SERVA.
